CLAIM

The ornamental design for a stand for electronic device, as shown and described.

DESCRIPTION

FIG. 1 is a front perspective view of a stand, having a supporting member and an electronic device holder, for electronic device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the supporting member;

FIG. 10 is a rear perspective view of the supporting member;

FIG. 11 is a front perspective view of the electronic device holder;

FIG. 12 is a rear perspective view of the electronic device holder;

FIG. 13 is a front perspective view of the stand for electronic device in which the supporting member and the electronic device holder are shown separated for clarity of disclosure; and,

FIG. 14 is a rear perspective view of the stand for electronic device in which the supporting member and the electronic device holder are shown separated for clarity of disclosure. The two apertures which are depicted by broken lines form no part of the claimed design. The remainder of the broken lines illustrates portions of the stand that form no part of the claimed design.
